HEADLIGHT

Filed Feb. 4, 1926

By *Frank B. Harrman, Raymond W. Darby*
Attorneys

UNITED STATES PATENT OFFICE.

FRANK BENJIMAN HARRMAN, OF DECATUR, ILLINOIS.

HEADLIGHT.

Application filed February 4, 1926. Serial No. 35,993.

This invention relates to new and useful improvements in headlights, and has for its principal object the provision of means to deflect certain rays of light from the illuminating means to impinge a lens of a particular type whereby a flood light of such dimensions will be sent from the headlight as to thoroughly illuminate objects laterally of the headlight when either driving forward or in making turns.

Another object of the invention resides in the provision of a headlight having a hemi-spherical lens in combination with means for deflecting and reflecting rays of light to all surfaces of the lens, provision being made in the combination to permit substantial unobstructed passage of certain of the rays to illuminate a substantial distance ahead, while the direct rays of light are cut off by the lens to prevent any blinding glare.

A further object of the invention resides in the provision of a headlight having a hemi-spherical lens to resemble a human eye.

Other objects and advantages of the invention will become apparent during the course of the following description.

In the accompanying drawing which forms a part of the description and wherein like numerals are employed to designate like parts throughout the views.

Figure 1 is a longitudinal section of the headlight employing my invention.

Figure 2 is a transverse section of the same taken on the line 2—2 of Figure 1, and

Figure 3 is a front elevation of the headlight with parts of the lens broken away to show the laminated structure thereof.

Referring now more in detail to the drawings and wherein for the purpose of illustration, I have shown the embodiment of my invention which is at present preferred, the numeral 4 designates the headlight casing of any desired construction, although it should follow more or less closely to a hemi-spherical or parabolic configuration as is customary. The forward end 5 of this casing is slightly enlarged or flared to co-operate with a detachable rim 6 in providing an annular channel to receive parts of the headlight to be hereinafter described.

A reflector 7 of any desired type is positioned in the posterior part of the casing 4 and is equipped with a central flanged aper-

ture 8 to align with the central orifice in the casing 4 for the passage of the incandescent bulb socket 9 so as to dispose the incandescent bulb 10 in front of the reflector 7 as shown. Any desired medium may be employed for varying the position of the incandescent light axially of the reflector 7. The outer end of the reflector is provided with an out-turned flange 11 having a depressed circumferential groove therein for the reception of a cushioning ring 12, and the free edge of this flange is turned at right angles to be received in the annular groove formed by the rim of the headlight 10 co-operating with the end 5 of the casing.

The lens 13 of the headlight is substantially hemi-spheric to closely resemble the cornea of the human eye, and comprises a laminated structure consisting of inner and 75 outer hemi-spheric clear glass shells 14 and 15 respectively and an intermediate translucent hemi-spherical lens 16 fitting closely to one another. The edge of the shell 15 is provided with an outwardly extending flange 80 17 adapted to be received in the groove formed by the headlight rim, while the shells 14 and 16 have no flanges and are held in contact with each other and with the shell 15 throughout their areas in a manner which 85 will be presently described. The intermediate translucent lens 16 may be of the milky white type, vitreous or of any other material which will render the lens non-glaring.

The central portion 18 of any of these 90 shells 14, 15 or 16 is shaded as shown in Figure 3 to imitate the pupil of an eye and to cut off direct rays from the illuminating means, although I prefer to stamp an iridescent color upon the intermediate lens 16. 95 Arranged in spaced relation to the shaded area 18 is a second shaded ring-like area 19 of substantially circular configuration but having its inner edge resembling a hypocycloid to resemble the iris of an eye and to 100 provide a translucent space 20 between the two shaded areas 18 and 19.

Between the illuminating means 10 and the hemi-spheric shell 13, a crystalline shell 21 is positioned with its outer edge received 105 and clamped between the flange 11 of the reflector and the flange 17 of the lens 15 by means of the usual detachable rim 6. In this connection it will be observed that the edges of the lenses 14 and 16 abut the shell 21 to maintain these lenses stable. This crystalline shell which is made of clear glass,

is substantially trumpet shaped to flare outwardly and is hollow for the purpose of mounting within its inner truncated end 22 a concavo-convex lens 23 directly in front of the incandescent bulb 10. This concavo-convex lens has its posterior concavity greater than its anterior convexity so as to deflect rays of light throughout the entire area of the hemi-spheric lens 13. In order to completely diffuse the light rays deflected by the lens 23, I locate a circular piece of shot silk fabric 24 directly in front of this lens and attach it to the shell 21 by crimping the edge of the fabric and attaching it to the shell in any suitable manner.

From the foregoing description, it will be apparent that some of the rays of light from the incandescent bulb 10 will be deflected by the concavo-convex lens 23 so as to spread or disperse these rays whereby they will be directed to the entire area of the hemi-spherical lens 13 thereby permitting the headlight to shed a flood of light both laterally and forwardly thereof. The most direct rays of light will be cut off by the shaded portion 18 of the lens 13, but some rays will be permitted to pass through the space 20 to illuminate objects a substantial distance ahead of the light, while the shaded portion 19 indicating the iris will cut off other of the light rays which usually cause the glare. The inner layer 14 of the lens 13 serves as a medium for the expansion of the light rays, although if desired this may be eliminated. Due to the shot silk screen 24 being positioned in front of the lens 23, and the lens 16 being translucent, it will be obvious that the rays of light are thoroughly diffused; the lens 16 acting to diffuse whatever rays of light that are reflected by the reflector 7 without passing through the screen 24.

It is to be understood that various changes in the size, shape and arrangement of parts may be resorted to without departing from the scope of the appended claims.

I claim:

1. A headlight comprising the combination of a casing having a reflector, illuminating means, a hemispherical shell having a central shaded portion, a lens positioned between said illuminating means and said hemispherical shell to permit passage of the direct rays from said illuminating means to said shaded portion of said hemispherical shell and to deflect other rays through other portions of the hemispherical shell, and a silk screen positioned in front of said lens.

2. A headlight comprising the combination of a casing having a reflector, illuminating means, a hemispherical shell having a shaded central portion, a concavo-convex lens stationed between the illuminating means and said hemispherical lens to permit passage of the direct rays from said illuminating

means to said shaded portion of said hemispherical lens and to deflect other rays through other portions of said hemispherical lens, and a fabric screen positioned in front of said concavo-convex lens.

3. A headlight comprising the combination of a casing having a reflector, illuminating means, a hemispherical translucent lens having centrally disposed spaced shaded portions separated by a translucent portion, a crystalline shell positioned between the illuminating means and said hemispherical lens, and a concavo-convex lens supported by said crystalline shell for directing direct rays to said shaded portions and deflected rays through the translucent portion arranged between the shaded portions.

4. A headlight comprising the combination with a casing having a reflector, illuminating means, a hemispherical translucent lens having a central shaded portion, said hemispherical lens projecting forwardly beyond said casing, a trumpet-shaped plain crystalline shell positioned in front of said illuminating means within said casing and adjacent the forward edge thereof, a concavo-convex lens mounted in said trumpet-shaped shell and having its axis coincident with the adjacent lens, and a fabric screen in front of said concavo-convex lens.

5. A headlight comprising the combination of a casing having a reflector, illuminating means, a hemispherical shell having a central shaded portion, a trumpet-shaped plain crystalline shell positioned in front of said illuminating means to permit passage of rays from said illuminating means to the entire inner surface of said hemispherical lens, a concavo-convex lens mounted in said trumpet shaped shell and having its axis coincident with the aforesaid lens to permit passage of direct rays from said illuminating means to said shaded portion of said hemispherical lens, and fabric diffusing means positioned in front of said concavo-convex lens.

6. A headlight comprising the combination of a casing having a reflector, illuminating means, a hemispherical lens having a central shaded portion, said hemispherical lens projecting forwardly beyond said casing, a trumpet-shaped crystalline shell positioned in front of said illuminating means within said casing and adjacent the forward edge thereof, and a concavo-convex lens mounted in said trumpet shaped shell and arranged adjacent the forward edge of said casing and adjacent the edge of said hemispherical lens to cause direct forward rays from said illuminating means to pass to said shaded portion of said hemispherical lens and other rays from said illuminating means to pass by deflection through the other portions of said lens.

FRANK BENJIMAN HARRMAN.
